FIBER RUG

Alan Brown, Higganum, Conn., assignor to Congoleum-Nairn Inc., Kearny, N.J., a corporation of New York

Filed June 27, 1956, Ser. No. 594,133

3 Claims. (Cl. 139—420)

This invention relates to woven fiber rugs and particularly to such rugs having a scintillating appearance.

Fiber rugs are conventionally woven from paper threads of various colors. The paper threads are prepared by slitting rolls of paper into narrow bands and then twisting two or more of the narrow bands together in a twisting machine. A decorative effect is obtained by forming the paper threads of paper bands of two or more colors thereby giving it a striped appearance. Fibers of cotton, silk, linen, flax, jute, ramie, mineral fiber, and, nylon, rayon and other synthetic fibers, or the like have been added in the twisting operation which when incorporated into a rug give the rug a more luxurious appearance. The variations which can be produced by this method are quite limited and therefore the patterns which can be produced are restricted. Heretofore it has been attempted to incorporate in fiber rugs various materials to give the rug a scintillating appearance. Some of these attempts have resulted in rugs having a pleasing appearance but which can not withstand ordinary usage. Other attempts have resulted in rugs which, while possessing a scintillating appearance have either an unpleasant appearance or have lost their overall color characteristics.

A general object of the invention is to produce a fiber rug having a scintillating appearance.

A more specific object is to produce such a rug without detracting from its overall color characteristics. A further object is to produce a rug having a novel design in an economical and practical manner.

In accordance with the invention a rug is produced having a scintillating appearance but which retains its overall color characteristics created by the color of the paper used in weaving the paper threads. The rug is formed by having its filling formed of paper threads wound spirally with transparent or translucent bands of plastic material. The plastic material is of such a nature that it will not be affected by the wear and use given the conventional rug. The transparent or translucent band enables the color of the rug to show through the band whereby the rug maintains its overall color characteristics while still having a scintillating appearance. The sparkle or scintillating appearance of the rug is greatly increased by utilization of a band of plastic material having a crinkled appearance thereby supplying many additional light reflecting surfaces without distracting from the overall color characteristic.

Other objects, features and advantages of the invention will be better understood from the following detailed description when it is read in conjunction with the several figures of the drawing in which:

Fig. 1 is an enlarged view of a fiber thread.

Fig. 2 is an enlarged view of a second fiber thread.

Fig. 3 is a cross-section of the fiber thread of Fig. 2.

Fig. 4 is a longitudinal view partially broken away of the fiber thread of Fig. 2.

Fig. 5 is a fragment of a reversible fiber rug containing the fiber thread shown in Fig. 1.

2

The filling for a fiber rug made according to the invention is prepared by twisting together paper bands formed of kraft paper or the like and spirally wrapping about the periphery thereof a plastic material in the form of a transparent or translucent band. The filling thread includes at least two paper bands 10 and 11 uniformly twisted around themselves to form a round thread of comparatively large cross-section as regards the thickness of the original band. About this thread is wound the thin plastic band 12. The plastic band can be wound about the paper thread in a separate operation or it can be wrapped around the paper thread by the conventional twisting machine during the forming of the thread. It is important, however, in wrapping the plastic band about the paper bands that the synthetic plastic band be only on the surface and not incorporated in the body of the thread. In this manner maximum reflectivity of the synthetic plastic band can be obtained. The plastic band should cover less than half of the surface area of the thread and preferably less than one-third of the area.

A similar paper thread can be prepared by twisting paper bands of different colors as indicated at 13, 14 thereby forming a thread having a striped appearance. The threads can also be formed so that the color changes 25 are staggered to produce bands of varying widths of color. A thin band of transparent or translucent material 12 is wrapped about the striped thread. In this manner the plastic band assumes the color characteristics of the striped paper thread because of its transparency. The 30 color of the thread and therefore the color of the rug is not altered by the addition of the transparent or translucent plastic band.

The paper threads, thus formed, can be of any suitable length and thickness, depending upon the purpose 35 for which they are to be utilized. In forming a light weight rug, a thread of comparatively small diameter would be used whereas in forming a heavier rug a larger thread will be used.

The thread having the plastic band wrapped about it 40 is then incorporated in a rug as the filling. The warp threads used in the fiber rug are made in a similar manner as the filling except they do not have the plastic material wrapped about their periphery. It is essential to the invention that the filling thread is the only thread 45 wrapped with the plastic band. A typical rug construction is illustrated in Fig. 5. One continuous twisted thread forms the filling 15. A plurality of other differently colored paper threads 16, 17, 18 form the warp and are woven with the filling in such a manner that one 50 of the paper threads 16 constitutes the inner layer of the rug for a substantial length and another thread 17 constitutes the outer or upper layer of the rug for the same length. The rug is provided with a non-raveling selvage edge 19 which is formed by looping back the filling 55 thread 15 at the edge of the rug, thus producing a non-raveling finished running edge.

The woven rug is cut into suitable lengths according to the size of rug desired, and the ends are finished off in any suitable manner to prevent unraveling. One 60 method of finishing is by folding a strip of binding material 20 of suitable width over the raw edges of the woven fabric. The binding material is then secured to the marginal edge of the rug by parallel lines of stitching 21 and 22 extending through the marginal edge of the rug from front to back and traversing the surface of the fabric from one selvage edge 19 to the other.

Rugs and floor coverings produced as described have a distinctive brilliant and attractive appearance, possess 65 exceptional wearing qualities and resist wear and tear under stress. The scintillating appearance of the rug can be greatly increased by using a synthetic plastic band which has been crinkled. This can be readily accom-

plished by passing the band through a machine which deforms the surface such as an embossing machine, thereby producing irregularities in the surface and creating a large number of light reflecting areas.

The plastic material selected is preferably a polyester such as a polymer, known as polyethylene terephthalate, formed by the condensation of ethylene glycol and terephthalic acid. Such a material is sold under the name "Mylar" by E. I. du Pont de Nemours & Co., of Wilmington, Delaware. Other synthetic resinous materials can be used however such as vinyl resins which include vinyl chloride, copolymers of vinyl chloride and vinyl acetate or other vinyl esters, polyethylene, polyurethanes and similar materials. A prime requisite in selecting a plastic material is its ability to withstand wear for a long period of time when incorporated in a rug. The tensile strength of the material should exceed 15,000 pounds per square inch and it should have a high tear strength of over 15 grams when tested on a conventional "cellophane tear tester." The plastic band is preferably from $\frac{3}{32}$ to $\frac{1}{2}$ inch in width and from 0.5 to 1.5 mils thick. The ability of polymers formed by the condensation of ethylene glycol and terephthalic acid to withstand such wear is outstanding.

Any departure from the above description which conforms to the present invention is intended to be included within the scope of the claims.

What is claimed is:

1. As an article of manufacture, a reversible woven fiber rug having a scintillating appearance, comprising a warp and a filling both made of paper thread, and a thin

transparent plastic band crinkled so as to provide many light reflecting surfaces, spirally wrapped around the filling thread so as to cover less than half of its outer surface.

2. As an article of manufacture, a woven fiber rug comprising a warp and a filling both formed from paper thread, and a thin, transparent plastic band crinkled so as to provide many light reflecting surfaces wound around the filling thread so as to cover less than half of its outer surface to give a scintillating effect to the rug, the plastic band having a tensile strength greater than 15,000 pounds per square inch and a tear strength of over 15 grams and being from $\frac{3}{32}$ to $\frac{1}{2}$ inch in width and from about 0.5 to 1.5 mils thick.

3. As an article of manufacture, a reversible fiber rug comprising a warp and a filling both formed from paper thread, and a thin, transparent band crinkled so as to provide many light reflecting surfaces, wound around the filling thread so as to cover less than half of its outer surface to give a scintillating effect to the rug, said band being formed of polyethylene terephthalate resin.
